UNITED STATES PATENT OFFICE

2,437,133

BABY FEEDER

Walter M. Sirks, Columbus, Ohio

Application November 1, 1945, Serial No. 626,079

6 Claims. (Cl. 248—105)

1

This invention relates to improvements in baby feeding devices and has for its object to provide a baby feeder consisting of an adjustable stand and means for supporting a feeding bottle flexibly mounted thereon.

Another object of this invention is to provide an adjustable feeding bottle holder of a nature to be supported upon a baby bed, high-chair, tray, table, or the like.

A further object of the invention is to provide a baby feeder angularly and vertically adjustable.

A still further object of my invention is to provide a feeding bottle holder on which a bottle may have vertical and horizontal pivotal movement.

Other features and advantages will become more readily apparent from the following description and the accompanying illustrative drawings in which:

Figure 1 is a perspective view of my baby feeder,

Figure 2 is a front elevational view thereof, parts being removed, and

Figure 3 is a side elevational view.

In the accompanying drawings as above enumerated and in the following specification, like characters of reference indicate like parts throughout and in which 10 indicates a nursing bottle holder which consists of an easel 11 formed of an inverted U-shaped member 12 and a rear leg member 13 hingedly connected thereto along their upper edges 14 and 15. The member 13 is slidably held to an anchor member 16 by means of an elastic band 17, the ends 18 and 19 of which are secured to the edges 20 and 21 of said anchor, the two members 13 and 16 together forming a telescopic rear leg for the device. The upper ends of the legs 22 and 23 of said U-member are beveled as at 24 and 25. Midway of the head 26 of the U-member, a cut-out 27 is provided of a width to receive the bottom end 28 of a feeding bottle 29, said end seating against the inner surface 30 of the member 13. Fixed to the edge 15 of member 13 adjacent each side of the cut-out 27 are the ends 31 and 32 of an elastic 33, to the center 34 of which is fixed an end of an elastic 35. The outer end 36 of the elastic 35 is attached to an elastic ring 37 adapted to be looped over the neck 38 of the bottle 29 to bear against the under shoulder 39 thereof, whereby said bottle will be held in an inclined position upon the border edge 39 of said cut-out 27. Secured to said head portion 26 and slightly spaced from the terminals 40 and 41 of the edge 39 are the

2

ends 42 and 43 of an elastic 44, which is seated around the central portion of the bottle and which is secured at its center 45 to the elastic 35. The above-described elastic harness which I shall refer to as a whole by the character 46, is of a size and character to fit tightly upon the bottle 29 to hold it in a normally inclined position as illustrated, but will allow a free universal movement thereof by a nursing child. The angle of the device when in operative position as indicated in Figures 1 and 3 of the drawings, is adjustable through means of its telescopic members 16 and 13.

The anchor 16 is of sufficient weight to hold the device in set-up position against accidental upset through movement of an infant nursing from the bottle, but which it can readily throw over when through nursing by simply raising the bottle out of its way, thereby causing an over-turn of the device. The members 12 and 13 are held normally spread apart by a leaf 47 hinged at 49 to the header edge 49' connecting legs 22 and 23. To the free edge 48 of said leaf is connected springs or elastic 48', also connected to the upper end of member 13, whereby member 47 is normally held raised to hold the legs of the easel fixedly spaced apart by leaf 47, may be drawn down against the tension of the springs to collapse the easel (see Figure 3). The lower end 50 of the anchor 16 is provided with a slot 51 through which a strap 52 is threaded and which strap is adapted to be secured around the tray of a high-chair when the device is to be used thereon, a buckle 53 being provided on the strap whereby it may be adjustably attached to the tray.

In case it may be desired to raise the bottle 29 higher than normally necessary, I provide a pair of extension legs 54 and 55 which may be telescopically adjusted to the free ends of legs 22 and 23 and held frictionally clamped thereon by means of a series of elastics 56.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention, that which I claim as new and desire to procure by Letters Patent is:

1. A baby feeder comprising an easel having a pocket formed in its upper end, means for holding a bottle seated therein, said means consisting of a harness attached to the easel and fitted upon the bottle in a manner to give the bottle universal movement, means for adjusting the angular position of the easel, means for adjustment of the height of the bottle, said harness being elastic and including a loop for the nipple end of the bottle, said height adjusting means consisting of a pair of attachable leg ends frictionally engageable with the legs of the easel, an anchor for supporting said easel and forming a part of said angular adjusting means, and means for securing the anchor to a tray.

2. A baby feeder comprising an easel having a pocket formed in its upper end, means for holding a bottle seated therein, said means consisting of a harness attached to the easel and fitted upon the bottle in a manner to give the bottle universal movement, means for adjusting the angular position of the easel, means for adjustment of the height of the bottle, said harness being elastic and including a loop for the nipple end of the bottle, said height adjusting means consisting of a pair of attachable leg ends frictionally engageable with the legs of the easel, and an anchor for supporting said easel and forming a part of said angular adjusting means.

3. A baby feeder comprising an easel having a pocket formed in its upper end, means for holding a bottle seated therein, said means consisting of a harness attached to the easel and fitted upon the bottle in a manner to give the bottle universal movement, means for adjusting the angular position of the easel, means for adjustment of the height of the bottle, said harness being elastic and including a loop for the nipple end of the bottle, and said height adjusting means consisting of a pair of attachable leg ends frictionally engageable with the legs of the easel. 40

4. A baby feeder comprising an easel having a pocket formed in its upper end, means for holding a bottle seated therein, said means consisting of a harness attached to the easel and fitted upon the bottle in a manner to give the bottle universal movement, means for adjusting the angular position of the easel, means for adjustment of the height of the bottle, said harness being elastic and including a loop for the nipple end of the bottle, and said height adjusting means consisting of a pair of attachable leg ends.

5. A baby feeder comprising an easel having a pocket formed in its upper end, means for holding a bottle seated therein, said means consisting of a harness attached to the easel and fitted upon the bottle in a manner to give the bottle universal movement, means for adjusting the angular position of the easel, means for adjustment of the height of the bottle, said harness being elastic and including a loop for the nipple end of the bottle.

15 6. A baby feeder comprising an easel having a pocket formed in its upper end, means for holding a bottle seated therein, said means consisting of a harness attached to the easel and fitted upon the bottle in a manner to give the bottle universal movement, means for adjusting the angular position of the easel, means for adjustment of the height of the bottle, and said harness being elastic and including a loop for the nipple end of the bottle.
